UNITED STATES PATENT OFFICE.

MITCHELL F. McCARTHY, OF CHICAGO, ILLINOIS.

PRESSURE-REGULATOR FOR LAMPS AND THE LIKE.

No. 921,272.

Specification of Letters Patent.

Patented May 11, 1909.

Application filed November 26, 1906. Serial No. 345,234.

To all whom it may concern:

Be it known that I, MITCHELL F. McCARTHY, a citizen of the United States, residing at Chicago, in the county of Cook and State 5 of Illinois, have invented certain new and useful Improvements in Pressure-Regulators for Lamps and the Like, of which the following is a specification.

My invention aims to provide an improved 10 and simple means for regulating the pressure and amount of combustible gas delivered to a lamp burner or the like, and maintain the same constant although the pressure in the supply main or pipe may vary within comparatively wide limits.

I propose to actuate a controlling or pressure-reducing valve by means of a diaphragm upon which the regulated pressure of the gas acts, opening the same more when the pressure 20 diminishes and closing it more or less as the pressure rises. In order to conduct the gas directly to the burner and in as straight a path as is convenient, I allow the same to pass through an aperture in the 25 diaphragm, a desirable construction employing a tube extending through the diaphragm. This is an extremely simple structure and is found to work efficiently and satisfactorily. In addition to the gas pressure 30 I use two springs acting on the diaphragm, one, the compression spring, acting in opposition to the gas pressure, while the other, the compensating spring, acts in conjunction with the pressure exerted by the 35 gas.

Various other features of my invention will become apparent to those skilled in the art as the following description of the invention is read in connection with the accompanying 40 drawings forming a part of this specification.

Figure 1 on said drawing is a perspective view of a gas burner equipped with one embodiment of my pressure regulator; and 45 Fig. 2 is a longitudinal section of the structure shown in Fig. 1.

On the end of a gas supply pipe 10, by means of a screw-threaded or other suitable connection, I mount a diaphragm clamping member 11 which acts also as a conduit and provides a passage for the gas. Within this 50 circular member 11 is a partition 12 having a central conical valve port or opening 13, the partition being in reality an inwardly projecting round ledge or shelf. The upper part 55 of member 11 is flared out and is of much

greater diameter than the lower portion. The circular upwardly-projecting marginal flange 14 on the top of the diaphragm clamping member 11 is screw threaded on its outer 60 surface to engage the internal threads of a round depending flange 16 on a similarly-flared diaphragm clamp 15. Between these two clamps 11 and 15 the periphery of a circular diaphragm is adapted to be grasped 65 and securely held. This diaphragm includes a round leather or kid disk 17, preferably enameled on one side or otherwise rendered impervious to the passage of gas therethrough. Any other flexible material 70 through which gas cannot pass may be employed in place of the leather mentioned. In order to stiffen this leather diaphragm I use on one side of it a thin metal disk or round sheet 18 of smaller diameter than the 75 leather diaphragm 17 so that its outer edge is not gripped between members 11 and 15.

The burner tip 19 is inserted in the top or upper end of a burner 20 which, at its lower end, is secured to the top of a gas conducting 80 tube 21, which in turn is soldered at its lower end within a hollow diaphragm fastener 22 which in effect forms a continuation of or part of the tube. Fastener 22 has a flat seat or enlargement 22^a adapted to bear against 85 the under side of disk 17 and an adjacent screw threaded part 23 adapted to extend upwardly through and beyond central apertures in the leather and metal disks. Above these disks is a nut 24 engaging the threads 90 of fastener 22 and is employed to firmly clamp or grip the leather and metal parts of the diaphragm between itself and the flat seat 22^a thereby securely fastening the tube to the diaphragm. Beneath the diaphragm 95 the fastener 22 has a number of radial holes 25 communicating with its longitudinal central aperture, and screwed into the lower end of the member 22 is a valve stem 26 carrying at its lower end a conical valve 27 adapted to 100 open and close the port opening 13. A compression spring 28 is interposed between the diaphragm clamping nut 24 and an adjustable nut 29 recessed on its interior to receive the top portion of the spring and screw 105 threaded on its exterior to engage the internal threads 30 at the upper end of diaphragm clamping member 15. Also mounted on the top of member 15 is a cylindrical burner guide and support 31 cut away on two sides 110 at 32 to permit access to the knurled end 33 of the spring-adjusting nut 29. Between the

ledge or circular shoulder 12 of the member 11 and the diaphragm fastening 22 I provide a compensating spring 34 which acts upon the diaphragm in opposition to spring 28 and in conjunction with the pressure of the gas 5 which has passed through the valve port 13.

Assuming that the parts of the regulator have been assembled in the proper manner and correctly adjusted, they will occupy the 10 position shown in Fig. 2, and under normal conditions the valve 27 would leave the port 13 partially open, as shown. The gas arriving at the regulator through pipe 10 passes through the opening 13, through the radial 15 holes 25 and the central aperture of the fastener 22 which, as stated above, in reality forms a part or continuation of the tube 21, and through the latter to the burner 20 and tip 19 where the combustion takes place. If 20 the pressure rises above that for which the regulator is adjusted it presses upon the diaphragm 17 lifting the same and the attached valve 27 so that the port opening 13 is somewhat closed thereby reducing the pressure of 25 the gas delivered to the burner. If, on the other hand, the gas pressure decreases spring 18 overcomes the combined pressures of the gas and compensating spring 34 and causes 30 the diaphragm to descend, thereby opening the valve port wider and admitting more gas to the burner or tip. It should be understood that the spring 34 is weaker than the compression spring 28 and is employed in order that the device may be sensitive under 35 low pressures. Particular attention is directed to the fact that the gas is delivered to a burner or the mixing chamber of a mantle lamp or the Bunsen form of burner where the air is admitted through an aperture of the

diaphragm, in fact through a tube extending 40 through the diaphragm. It will be noticed that because of this construction the gas has a comparatively direct path from the supply pipe 10 to the burner 20.

To those well acquainted with this art it will 45 be apparent that many minor mechanical changes may be made in the structure shown and described without departing from the substance of my invention.

I claim:

In a pressure regulator for lamps or the like, the combination of a conduit for the passage of a fluid, said conduit having a valve port and a shoulder or ledge, a diaphragm closing the passage through said conduit and 50 acted upon by the pressure of said fluid, a valve connected to and movable with said diaphragm and adapted to control the passage of said fluid through said valve port, a compensating spring interposed between said 55 diaphragm and said shoulder or ledge, a rigid tube to conduct said fluid to the burner, said tube extending through said diaphragm and communicating with said conduit between 60 said diaphragm and said valve and valve port, a compression spring pressing against 65 said diaphragm in opposition to the action of said compensating spring, said compression spring surrounding said tube, and a screw threaded nut encircling said tube and adapted to adjust the pressure of said compression 70 spring on said diaphragm, substantially as described.

MITCHELL F. McCARTHY.
